pany, East Pittsburgh, Pa., a corporation of
Pennsylvania

Application February 9, 1934, Serial No. 710,409

18 Claims. (Cl. 264—3)

My invention relates to valves and valve operating mechanism for regulating the speed of prime mover apparatus, for example, elastic fluid turbines; and it has for a broad object to provide apparatus of this character which is of improved construction and arrangement of parts, and also one which effectively controls the prime mover apparatus throughout its speed range.

10 Apparatus of this character heretofore known to me usually comprises a valve body, a valve in the body and including a stem extending exteriorly thereof, a relay for opening and closing the valve including a secondary element connected to the valve stem and a primary element movable to regulate the application of an operating force to the secondary element, and a follow-up mechanism for restoring the primary element to neutral position upon movement of the main valve in either direction to terminate movement of the latter. The follow-up mechanism is usually in the form of a lever connecting the valve stem and primary element and including a fulcrum element about which the lever rocks.

Depending upon the desired effect, initial movement of the primary element to provide movement of the secondary element and main valve in the desired direction, has been effected in prior apparatus of this type in a variety of ways. For example, initial movement of the primary element may be effected by variations in a governing force which is a function of the speed of the prime mover and in such cases the governing force is opposed by a spring, the deflection of which may be varied manually to effect a variety of speed adjustments. The follow-up mechanism usually acts through the spring to return the primary element to neutral position. Another example of prior means for effecting initial movement of the primary element to either main valve opening position or closing position is by a simple manually operated control means. A still further example is a combination of the governor and the manual control.

In prior art structures of this type, where it is desired to regulate the speed of the turbine by varying the deflection of the governor spring to change the speed setting of the governor, or where it is desired to regulate the speed by moving the primary element in a main valve opening or closing direction, movement of the primary element is usually effected by manual movement of the fulcrum element of the follow-

up lever in directions normal to the direction of extent of the lever. Heretofore, the fulcrum element has been placed close to the primary element at the side opposite the main valve, thereby resulting in a small and fixed ratio of movement of the primary element with respect to the main valve movement. Such an arrangement is considered desirable in order that the length of movement required to operate the primary element be kept at a small value. A further advantage of such an arrangement, which is particularly applicable to the type employing a governing spring, is that only a small length of governing spring is required. Such an arrangement operates well when the main valve is away from its seat. However, with such a structure, as the main valve approaches its seat, a poor regulation is had because the amount of movement of the main valve required to move the primary element the short distance back to neutral position produces too great a change in the flow of elastic fluid to the prime mover.

It is therefore, a further and more specific object of my invention to provide, in a valve operating mechanism, for a decreasing ratio of main valve movement to primary element movement as the main valve approaches its seat so as to give a close and effective regulation at such positions, and to provide for an increasing ratio of main valve movement to primary element movement as the main valve leaves its seat so as to maintain the advantage of a small size of primary element and a short governor spring.

It is still a further object of the present invention to combine the manual adjustment feature utilized in valve operating mechanism of this character with the feature of varying the ratio of primary element to main valve movement so that as the position of the adjusting element is changed to move the primary element in either direction to vary the position of the main valve, the ratio of primary element movement to main valve movement will be changed to correspond to the new position of the main valve.

The above objects are attained according to one embodiment of my invention by providing a longitudinally disposed slot in the follow-up lever, in placing the fulcrum element in the slot and in providing for manual movement of the fulcrum element along the slot in such a manner that as the fulcrum element approaches the primary element the ratio of main valve movement to primary element movement increases and at the same time the primary element is

5 moved in the direction to effect an opening movement of the main valve, and conversely as the fulcrum element is moved away from the primary element to decrease the ratio of main 10 valve movement to primary element movement, the primary element is also moved in a direction to close the main valve.

10 Another object of the present invention is to provide a structure which is comparatively cheap and at the same time is capable of regulating prime movers utilizing elastic fluid at relatively high temperatures. I accomplish this object by providing a main valve body of cast steel capable of standing up under the high temperatures, a relay mechanism of cast iron which is comparatively cheap to manufacture, and in securing the two together by steel rods which can be readily tapped into the cast iron relay and then welded to the cast steel valve body. 15 The rods in addition to being strong provide a connection which occupies a small amount of space and thereby offers the maximum of accessibility for assembling and adjustment and the small cross section of the steel rods reduces the transmission of heat from the valve to the operating mechanism to a minimum. In cases where a cast steel valve body is not needed, only the bonnet thereof may be made of cast steel and the rods welded thereto in the same manner. 20 These and other objects are effected by my invention as will be apparent from the following description and claims, taken in connection with the accompanying drawings, forming a part of this application, in which:

25 Fig. 1 is an elevation showing my improvement as applied to a steam turbine.

30 Fig. 2 is a transverse vertical section through a valve and relay for operating the valve of an elastic fluid turbine constructed in accordance 40 with my invention;

35 Fig. 3 is a fragmentary sectional view taken on the line III—III of Fig. 2 and illustrating the connection between the main valve stem and follow-up lever;

40 Fig. 4 is a fragmentary sectional view taken on the line IV—IV of Fig. 2 and illustrating the connection between the follow-up lever and normally-movable fulcrum element; and

45 Fig. 5 is a view similar to Fig. 2 illustrating a modified form of my invention.

50 Referring now in detail to the construction illustrated and particularly to the embodiment shown in Figs. 1 to 4, inclusive, I have shown my invention as applied to a conventional type 55 of steam turbine 10, to which motive steam is supplied by a pipe 11. Flow of steam to the turbine is regulated by a main valve 12 mounted within a valve body 13, which latter is preferably formed of cast-steel in order that it may 60 effectively stand up under high temperatures of steam.

65 The valve comprises a stem 14 extending exteriorly of the body and connected to a relay indicated in its entirety by the reference numeral 15. The relay is preferably disposed within a cast-iron casing 16, which is supported from the cast steel valve body 13 by means of steel rods 17 suitably tapped as indicated at 18 into the relay casing and welded, as indicated 70 at 19, to the cast-steel valve body.

75 The relay comprises a primary or pilot element 20, a secondary or operating element 21, and a follow-up lever 22 connecting the primary element and steam valve and including a fulcrum element 23 about which the lever rocks,

5 The secondary element is connected to the stem 14 of the steam valve for moving the latter to regulate the flow of steam to the turbine. The primary element serves to regulate the application of an operating force to the secondary element. The follow-up lever 22 is moved about its fulcrum element 23 by the main valve to restore the primary element to neutral or cut-off position upon movement of the main valve in either direction.

10 While, so far as certain of the broader aspects of the present invention are concerned the relay may be of any suitable type, I prefer to use a relay operated by fluid under pressure. As shown in Fig. 2, the secondary element 21 comprises an operating cylinder 24 formed in the casing 16, and an operating piston 25 movable within the cylinder 24 and connected by a rod 26 with the valve stem 14. The primary element comprises a pilot valve 27 slidably mounted in a stationary bushing 28 within the casing 16 and is movable to regulate the application of an operating fluid under pressure to the secondary element.

15 Downward movement of the operating piston 25 in a direction to close the main valve is effected by means of a compression spring 29 disposed between the upper side of the operating piston and the relay casing 16. Upward movement of the operating piston to open the main 20 valve is effected by fluid under pressure admitted to the operating cylinder beneath the operating piston and opposing the force of the spring 29. The fluid is admitted through a port 25 in the lower portion of the cylinder which 30 communicates with one end of a passage 31 drilled or cored in the relay casing and the upper end of this passage communicates with an annular series of ports 32 in the pilot valve bushing 28.

35 The pilot valve bushing 28 is also provided with a second annular series of ports 33 below the ports 32 and communicating with a pipe 34 which supplies operating fluid under a pressure, which, in this case, may be oil from any suitable source, for example, the oil may be supplied by a governing oil line 35 (Fig. 1), which latter is connected to the discharge of a governor pump 36 of the impeller type operated by the turbine shaft 37. The pilot valve bushing is also provided with a third annular series of ports 38 above the ports 32 and connected to a suitable discharge pipe 39.

40 As shown, the pilot valve 27 is of the piston type and includes a head portion 40 and a skirt portion 41. Two annular recesses 42 and 43 respectively, are provided on the exterior of the skirt portion 41 and they are separated by a piston portion 44.

45 In the neutral or cut-off position of the pilot valve, which is the position shown on Fig. 2, the piston portion 44 serves to blank off the ports 32 and thereby prevent operating fluid from either entering or leaving the lower portion of the operating cylinder 24. Should the pilot valve be moved upwardly from the position shown in the drawing, the ports 32 will be placed in communication with the ports 33 by the annular recess 42 and as a result operating oil under pressure will flow into the lower portion 50 of the cylinder and oppose the spring 29 with sufficient force to raise the piston 25 and open the main steam valve 12. On the other hand, should the pilot valve be moved downwardly from the position shown, the annular recess 43 55

will provide communication between ports 32 and ports 38 and oil will escape from the cylinder 24 to the discharge pipe 39 and thereby permit the spring 29 to move the piston 25 down 5 to close the main steam valve.

The present invention is shown as applied to the type of valve operating mechanism wherein the steam valve is controlled by hand until the speed of the turbine attains a certain predetermined minimum, and, for speeds above this minimum, the hand adjustment is used to change the speed setting of a governor which controls the steam valve. This type of construction is especially useful in marine installations wherein it is desired to control the turbine in the low speed or maneuvering range directly by hand and at the same time it is desired to have governor control for the turbine in the upper speed range. One example of this type of construction is described and claimed in my copending application, Serial No. 545,603 filed June 19, 1931, and assigned to the Westinghouse Electric & Manufacturing Company. A compression spring 45 engages at one end 25 thereof the under face of the head portion 40 of the pilot valve and engages at its other end an abutment 46 formed on the upper end of a plunger element 47 slidably mounted in the relay casing 16. The spring 45 surrounds a rod 48 fixed at one end to the plunger 47 and the other end thereof slidably fitting an opening 49 through the head portion 40. The upper end of the rod 48 is screw threaded and a pair of nuts 50, one for locking the other at any given 35 position on the rod, are threaded thereon at the top side of the head portion 40 and serve the dual function of providing for changing the initial deflection of the compression spring 45 and also, due to their engagement with the head portion 40, serve to pull the pilot valve down upon a downward movement of the plunger 47. The plunger is pivotally connected to one end of the follow-up lever 22.

The pipe 35 which delivers governing oil under pressure from the governor pump 36 driven by the turbine shaft, is connected to a chamber 51 above the head portion 40. Hence, the upper face of the head portion 40 is subjected to the governing oil pressure generated by the pump 36; this pressure being opposed by the compression spring 45 engaging the under side of the head portion. As the impeller pump is driven by the turbine shaft, the pressure of the oil in pipe 35 and in the chamber 51 will vary as the square of the speed of the turbine.

The position of the nuts 50 on the rod 48 determines the initial deflection of the compression spring 45, and hence determines the minimum speed of the turbine and corresponding governing oil pressure required to move the pilot valve down relative to the plunger 47. For speeds below this minimum the movement of the pilot valve is effected only by the position of the plunger.

As stated, the plunger 47 is connected to the main valve 12 by means of a follow-up lever 22. As shown in Figs. 2, 3, and 4, the follow-up lever comprises a pair of like bars 55 held in spaced relation by bolts 56 and 57. The bars are pivoted 70 at one of their ends to a pivot pin 58 carried by the plunger element 47 and are pivotally and slidably connected at their other end to the valve stem 14. The latter connection is effected, as will be seen from examination of Fig. 3, by 75 spaced rollers 59 and 60, connected to the valve

stem and engaging rails 61 and 62, respectively, which extend from and are rigidly secured to the inner sides of the bars 55. The rollers 59 and 60 are mounted on trunnions 63 and 64, respectively, carried by the coupling 65, which connects the valve stem 14 and operating piston rod 26. A tension coil spring 66 is connected at one end to the relay casing 16 and at the other end to the spacing bolt 57 and thereby serves to maintain the rollers 59 and 60 and 10 rails 61 and 62 in contact.

The fulcrum element 23 of the lever 22 is carried by the lower and outer end of a manually movable arm 67. As will be seen from an examination of Fig. 4, the fulcrum element is in the form of spaced rollers 68 fitting in aligned slots 69 formed, respectively, in the bars 55 and extending longitudinally thereof. The rollers are carried by the lower end of the operating arm 67 and such arm is fixed at its upper end to a control shaft 70 rotatably mounted in spaced ears 71 which depend from the relay casing. Any suitable means, such as a hand-operated lever 78 may be provided for rotating the shaft and thereby moving the rollers in the slots 69. 25 Movement of the operating shaft 70 will cause the axis of the fulcrum element 23 to move in an arc of a circle.

The dotted line *a* represents the center line of the groove 69 and the dot-and-dash line *b* represents the arc of travel for the fulcrum element 23 to the right of the position shown in Fig. 2, the arc of travel for the fulcrum element to the left of the position shown in that figure being coincident with the center line *a*. 35

Should the fulcrum element be moved to the left as viewed in Fig. 2, no movement will be imparted to the lever 22 or plunger 47 as the arc of movement of the fulcrum element is coincident with the center line *a*. On the other hand, 40 should the fulcrum element be moved to the right the lever 22 will be moved in a counter-clockwise direction about its pivotal and slideable connection with the stem 14 a distance depending on the distance between lines *a* and *b*, 45 thus moving the plunger 47 and pilot valve 27 upward the same distance. The distance between lines *a* and *b* becomes greater as the right-hand end of the slot is approached. Hence, the plunger 47 and pilot valve 27 is moved upward a progressively increasing amount as the fulcrum element approaches the right-hand end of the slot. 50

An auxiliary oil line 75 is provided which connects with the pipe 34. Oil under pressure from any suitable source (not shown) is supplied by the line 75. A valve 76 in the line 75 and a valve 77 in the pipe 34 serve to connect the ports 33 with either the auxiliary oil line 75 or with the governing oil pipe 35. 55

When it is desired to start the turbine the auxiliary line 75 is connected to pipe 34 by opening the valve 76 and closing valve 77. After the turbine speed is sufficient to generate sufficient oil pressure in the line 35 to operate the piston 25, the valve 77 may be opened and the valve 76 closed. 60

A small movement of the fulcrum element to the right, as viewed in Fig. 2, will result in an upward movement of the plunger element 47 and pilot valve 27 and cause operating oil to flow from the port 33 through the recess 42 to the port 32, and, from the latter, through the passage 31, to the under-face of the operating piston 25, whereby oil pressure below the latter causes up- 75

ward movement of the piston 25 to open the main valve 12. Movement of the main valve 12 in an opening direction will cause the follow-up lever 22 to rock about its fulcrum 23 and pull the plunger 47 and pilot valve 27 back to neutral or cut-off position. The amount of movement of the main valve required to move the pilot valve back to neutral position depends upon the relative lengths of the two lever arms, one lever arm being the distance between the fulcrum element and the pivotal and slidable connection with the valve stem 14 and the other lever arm being the distance between the fulcrum element and the pivot 58.

Further movement of the fulcrum element to the right will result in the pilot valve 27 being moved up again and in more oil being admitted beneath the operating piston and consequently in the main valve being opened still wider. For this more advanced position of the fulcrum element, more movement is required by the main valve to move the pilot valve back to neutral position because the fulcrum element has moved over further and the lever arm between the fulcrum element and the pivot 58 has become less and the other lever arm greater. Thus, the ratio of pilot valve movement to main valve movement decreases as the main valve leaves its seat and increases as the main valve approaches its seat. Less movement of the main valve is required to move the pilot valve back to neutral position as the main valve approaches its seat. Hence, closer regulation is had when the main valve is adjacent its seat, where increments of movement thereof cause greater changes in steam flow and turbine speed than are caused with the valve away from its seat.

Movement of the fulcrum element further and further toward the right will result in the main valve 12 being opened wider and wider and in the turbine speed being increased. When the speed of the turbine increases to a point where the resulting oil pressure in line 35 and chamber 40 is greater than the initial deflection of the spring, determined by the position of the nuts 50, downward movement of the pilot valve will be effected by the governing oil pressure on the top of the pilot valve. The spring 45 will then act as a governing spring, and, for this speed range, movement of the fulcrum element will serve to change the speed setting of the governing spring, and not in a direct manual movement of the pilot valve, as was the case where the speed of the turbine was below this range.

It will be observed that the minimum ratio of pilot valve movement to main valve movement is had at the higher speed, and in the governing speed range. Therefore, with my apparatus, a minimum length of governor spring is required, and a small travel of piston valve and consequently a small size of piston valve is required, as is the case with prior apparatus. However, at the same time, my apparatus, due to the varying of the lever arm ratio, provides a close regulation when the valve 12 is adjacent its seat.

Referring now to Fig. 5 of the drawings, it will be observed that I have shown a modified form of construction for controlling the flow of steam to a turbine, the principal difference being changes necessitated by positioning of the fulcrum element to one side both of the operating cylinder and of the pilot valve, instead of therebetween, as in Fig. 2. As in the previously described modification, I provide a main steam valve 12a disposed within a cast-steel valve body

13a and having an operating stem 14a extending exteriorly of the valve-body and connected by a coupling 65a with the lower end of an operating piston rod 26a, the other end of the latter being connected to an operating piston 25a movable in an operating cylinder 24a formed in a relay casting 16a formed of cast iron. Also, as in the previously described modification, the cast-iron casting 16a is supported from the cast-steel valve body 13a by steel rods 17a, and the piston 25a is moved down in the cylinder 24a by a spring 29a and is moved upward by operating oil under pressure opposing the spring pressure and admitted by port 30a from a drilled groove 31a connecting at its upper end with ports 32a in a pilot valve bushing 28a.

In this modification, the discharge ports 38a in the pilot valve bushing are provided below the ports 32a and the inlet ports 33a are provided above the ports 32a. The operating oil is supplied to the ports 33a by the pipe 34a and the discharge pipe 39a connects with the ports 38a. The pilot valve 27a is movable within the bushing 28a and is provided with annular recesses 42a and 43a on its exterior face separated by a piston portion 44a. Also, in this modification, the recess 42a which serves to connect the ports 32a with the operating oil ports 33a, is above the piston portion 44a; and the recess 43a connecting the ports 32a with the discharge ports 38a, is below the piston portion 44a.

The governing oil from pipe 35a is supplied beneath the head portion 40a instead of above as in the previously-described modification, and the governing spring 45a is a tension spring instead of a compression spring and connects a spring holder 80 secured to the head portion 40a by a threaded extension 81 and nut 82 and a spring holder 83 screwed to a screw-threaded portion 84 on a plunger 47a. The spring 45a surrounds a rod 85 which is an integral extension of the plunger 47a and engages at its upper end the spring holder 80. The spring holder 83 is in the form of a plunger and fits the cylindrical inner surfaces of the lower end of the bushing 28a.

The spring 45a will hold the spring holder 80 hard against the end of the rod 85 until the speed of the turbine is such that the pressure of the governing oil will overcome the force of the spring and move the piston valve 27a with respect to the plunger 47a. The initial deflection of the spring 45a, and hence, the governing and hand control speed ranges of the turbine, are determined by the position of the spring holder 83 on the portion 84; and this position may be varied by screwing the spring holder up or down on the portion 84. As will be readily seen, the principal difference of the construction of the pilot valve and governor spring of Fig. 5 over the construction shown in Figs. 1 to 4 is that, in Fig. 5, the spring 45a is a tension spring and in Figs. 1 to 4, inclusive, the spring 45 is a compression spring.

As in the previously described modification, a follow-up lever 22a connects the plunger 47a and the valve stem 14a, and the lever 22a comprises spaced bars 55a connected at one end by a pivotal and slidable connection with the coupling 65a on the valve stem 14a, and also connected to a pivot pin 58a carried by the lower end of the plunger 47a. The lever 22a is different from the lever 22 in that the fulcrum element 23a is disposed in slots 69a formed in extensions 86 of the bars 55a. The fulcrum element, instead of being disposed between the

main valve and plunger as in Figs. 1 to 4 is disposed in Fig. 5, at the side of the plunger 47a which is away from the valve stem 14a.

The fulcrum element 23a is movable along the slots 69a by an arm 67a fixed at its lower end to a shaft 70a, which is operated in any suitable manner, as by a hand-operated lever 78a. The center line of the slots 69a is indicated by the dotted line aa and the arc of movement of the axis of the fulcrum element 23a is indicated by the dot-and-dash line bb. The parts are shown in their relative position with the main steam valve 12a in closed position.

Movement of the fulcrum element 23a to the left, as viewed in Fig. 5, will result in a downward movement of plunger 47a and pilot valve 27a and in operating oil under pressure being admitted beneath the piston 25a from the port 30a, drilled groove 31a, ports 32a, recess 42a, ports 33a and pipe 34a. The resulting upward movement of the piston 25a acts to open the valve 12a and move the lever 22a upward about the fulcrum 23a and carry therewith the plunger 47a and pilot valve 27a back to neutral or cut-off position. Further movements of the fulcrum element 23a to the left will result in increased opening movements of the main valve 12a, and the operation of the valve operating mechanism will remain the same until the turbine speed reaches the governing range, where movement of the fulcrum element will then change the setting on the governing spring 45a as in the previously described modification.

Movement of the fulcrum element from a position corresponding to an open position of the main valve to the right or back toward the position shown, will result in an upward movement of the pilot valve from its neutral position and in the escape of operating oil from beneath the piston 25a through port 30a, drilled groove 31a, ports 32a, recess 43a and discharge ports 38a and discharge pipe 39a. As a result, the main valve 12a will be moved toward closed position carrying down with it the left-hand end of lever 22a. Downward movement of the lever 22a will cause the pilot valve also to be moved down to its neutral position.

As in Figs. 1 to 4 inclusive, the construction shown in Fig. 5 provides for a decrease in the ratio of main valve movement to pilot valve movement as the main valve approaches its seat so as to provide close regulation of the main valve for positions thereof close to its seat where a given movement of the steam valve produces a greater change in steam admission than is had when the valve is separated from its seat a substantial distance. Also, as the main valve 12a leaves its seat the ratio of main valve movement to pilot valve movement increases so that at the higher turbine speeds and in the governing speed range the ratio is quite large, whereby only a small size pilot valve and a small length governor spring is needed.

The respective lengths of the two arms of the lever 22a are the distance between the fulcrum element 23a and the connection between the lever 22a and the valve stem 14a and the distance between the fulcrum element and the pivot pin 58a. In the closed position the ratio of lever arm lengths is shown as being approximately 2 to 1. In the wide open position the ratio is shown as being approximately 4 to 1. Obviously, the structure may be designed to give a smaller ratio at the closed position and a higher ratio at wide open position, if it is desired. Due to

the character of the lever shown in Fig. 5, the lower limit of design could not be less than 1 to 1. For a large number of cases, sufficient latitude of design is permitted by the construction shown in Fig. 5. However, if smaller ratios are required, the design of Fig. 2 may be used. The lower limit in Fig. 2 is shown as being approximately 1 to 1. This may easily be made still lower by changing the construction so that the closed position of the fulcrum element would be at points in the slot 69 to the left of the position shown.

While I have shown my invention in several forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. The combination with a valve and its seat, of a relay including a secondary element connected to the valve, a primary element movable for controlling the application of an operating force to the secondary element, and means responsive to movement of the valve for restoring the primary element to neutral position in order to terminate movement of the secondary element; and means for moving the primary element and adjusting said restoring means so that the maximum ratio of primary element movement to secondary element movement occurs with the valve at its seat and so that the ratio diminishes the more the valve is separated from its seat.

2. Apparatus included in claim 1 wherein the restoring means is a lever connecting the valve and primary element and having a fulcrum element and wherein the means for moving the primary element and for adjusting the restoring means comprises a device for moving the fulcrum element along the lever and providing for increasing degrees of movement of the primary element toward its valve-opening position as the fulcrum element approaches the primary element.

3. The combination with a main valve and its seat, of an operating cylinder including a piston connected to the valve, a pilot valve controlling the admission and exhaust of motive fluid to and from the operating cylinder, follow-up mechanism arranged between the connected main valve and operating piston and the pilot valve for restoring the latter to neutral position upon movement of the main valve, and means for moving the pilot valve and adjusting the ratio of follow-up movement so that the ratio of main valve and operating piston movement to pilot valve movement is a minimum with the valve at its seat and increases with movement of the valve away from its seat.

4. Apparatus according to claim 3 wherein the follow-up mechanism includes a lever connecting the main valve and pilot valve, and wherein the pilot valve moving means includes a fulcrum for said lever movable therealong to effect movement of the pilot valve and at the same time to vary the ratio of pilot valve movement to main valve and operating piston movement.

5. The combination with a main valve and its seat, of a relay for controlling movement of the main valve and including a secondary element connected to the valve, a primary element mov-

able to control the application of an operating force to the secondary element, and a follow-up mechanism for restoring the primary element to neutral position upon movement of the main valve, the latter including a lever connected to the main valve and pilot valve and having a longitudinally disposed slot therein and a fulcrum element in said slot; and control means for effecting, simultaneously, initial movement of the primary element and variations in the ratio of main valve movement to primary element movement; said last-named means including an element connected to the fulcrum element and movable to effect movement of the latter along the slot in the lever.

6. Apparatus according to claim 5 wherein the control means provides for movement of the axis of the fulcrum element in an arc of a circle and the slot in the lever diverges away from the arc of movement of the axis of the fulcrum element as the latter approaches the primary element.

7. Apparatus according to claim 5 wherein the slot in the lever and the fulcrum element are disposed between the main valve and the primary element.

8. In valve operating mechanism, the combination with a valve, a servomotor connected to the valve for operating the latter, a movable element for controlling the application of an operating force to the servomotor, of a follow-up lever connecting the valve and movable element, for restoring the movable element to neutral position in order to terminate movement of the servomotor, a fulcrum element for the follow-up lever between the valve and movable element, and control means for moving the fulcrum element along said lever to secure movement of varying degree of the movable element whereby the application of operating force to the servomotor is regulated and the ratio of valve movement to control element movement is varied.

9. In valve operating mechanism the combination with a valve, a servomotor, connecting means between the valve and servomotor wherein by the latter serves to open and close the valve, and a movable element for controlling the application of an operating force to the servomotor for operating the latter; of follow-up mechanism connecting the valve and movable element for restoring the latter to normal or neutral position upon movement of the valve and including a lever having a fulcrum between its ends, the ends being connected respectively to the valve and movable element, and means providing for the movement of the fulcrum from a mid-position on the lever toward the end connected to the movable element to increase the ratio of valve movement to movable element movement as the fulcrum approaches the movable element and to decrease such ratio as it moves away from said element.

10. Apparatus according to claim 9 wherein the main valve serves to control apparatus wherein a governing force which is a function of the operation of the apparatus also acts on the movable element in the direction to secure movement thereof to effect closing movement of the main valve, and wherein for the first part of the movement of the fulcrum toward the movable element, movement of the latter is directly effected and for the last part of fulcrum movement toward the movable element a variation in application of the governing force to the movable element is effected.

11. In valve operating mechanism, the com-

bination with a main valve, a servomotor including a fluid-operated cylinder and a piston within the cylinder connected to the valve for opening and closing the latter, a pilot valve movable for controlling the application of an operating fluid to the piston, of a follow-up lever connecting the main valve and pilot valve for restoring the pilot valve to neutral position in order to terminate movement of the piston, a fulcrum element for the lever, and means providing for adjustment of the fulcrum longitudinally of the lever.

12. In a valve operating mechanism, a main valve, a servo-motor, a pilot valve for admitting and exhausting motive fluid to the servo-motor, a fulcrum pin, means providing for movement of the fulcrum pin toward and away from the pilot valve in a predetermined path, a follow-up lever connecting the main and pilot valves and having a slot within which the pin is disposed and extending longitudinally thereof, said slot having portions coincident and non-coincident with the path of movement of the pin and the parts being so arranged that, with the pin in the coincident portion of the slot, the main valve is closed and the non-coincident portion of the slot diverging from the path of movement of the fulcrum pin so that, with movement of the pin toward the pilot valve to increase the ratio of main valve movement to pilot valve movement, the servomotor is operated to move the main valve in an opening direction and so that, with movement of the pin along the non-coincident portion of the slot toward the coincident portion thereof to decrease the ratio of main valve movement to pilot valve movement, the servomotor is operated to move the main valve in a closing direction.

13. The combination with a turbine provided with an admission valve and means for developing a fluid pressure force which is a function of the turbine speed, of a servomotor for opening and closing the admission valve, a pilot valve for controlling the admission and exhaust of motive fluid to and from the servomotor to motivate the latter, said pilot valve having a piston face subject to said fluid pressure, a spring exerting its force against said pilot valve in a direction opposed to that of application of fluid pressure force, means for storing energy in the spring including a reciprocable member, a fulcrum pin, means providing for movement of the pin toward and away from the reciprocable member, and a lever pivotally connected to the admission valve and to the reciprocable member and having a slot within which the pin is disposed and extending longitudinally thereof, said slot diverging from the path of movement of the pin when the pin and lever are in such relative positions that the admission valve is closed so that, with movement of the pin toward the reciprocable member to increase the ratio of main valve movement to pilot valve movement, the servomotor is operated to move the main valve in an opening direction and so that, with movement of the pin in the other direction to decrease the ratio of admission valve movement to pilot valve movement, the servomotor is operated to move the admission valve in a closing direction.

14. The combination with a turbine provided with an admission valve and means for developing a fluid pressure force which is a function of the turbine speed, of a servomotor for opening and closing the admission valve, a pilot valve for controlling the admission and exhaust of motive

fluid to and from the servomotor to motivate the latter, said pilot valve having a piston face subject to said fluid pressure, a spring exerting its force against said pilot valve in a direction opposite to that of application of the fluid pressure force, means for storing energy in the spring including a reciprocable member, means for positively transmitting motion from the reciprocable member to the pilot valve in one direction so as to move the pilot valve to secure operation of the servomotor to move the admission valve in an opening direction, a fulcrum pin, means providing for movement of the pin toward and from the pilot valve in a predetermined path, a lever 5 pivotally connected to the admission valve and to the reciprocable member and having a slot within which the pin is engaged and extending longitudinally thereof, said slot diverging from the path of movement of the fulcrum pin when the pin and lever are in such relative positions that the admission valve is closed so that, with movement of the pin toward the reciprocable member to increase the ratio of admission valve movement to pilot valve movement, the servomotor is operated to move the main valve in an opening direction and so that, with movement of the pin in the other direction to decrease the ratio of admission valve movement to pilot valve movement, the servomotor is operated to move 10 the main valve in a closing direction.

15. In valve operating mechanism, the combination of a prime mover; a main valve for controlling the flow of elastic fluid to the prime mover; a relay for operating the main valve and comprising an operating cylinder, an operating piston within the cylinder and connected to the main valve for operating the latter, a pilot valve cylinder and a pilot valve for controlling the flow of an operating fluid to and from the operating cylinder so as to effect movements of the operating piston and main valve, the pilot valve having a piston face; means providing a governing fluid pressure varying with the speed of the prime mover; means providing communication of such governing fluid with the piston face of the pilot valve so as to effect movement of the latter toward neutral and closing position; a compression

spring engaging at one end the pilot valve at the side thereof opposite the piston face and engaging at the other end an abutment and arranged to oppose movement of the pilot valve effected by the governing fluid; follow-up mechanism including a lever connecting the main valve and the abutment, and a fulcrum element therefor; and means for moving the fulcrum element along the lever and providing for increase in the ratio of movement of the main valve with respect to movement of the pilot valve as the fulcrum element approaches the spring abutment. 10

16. In prime mover apparatus of the type utilizing high temperature elastic fluid as a motivating force, the combination of a valve body 15 formed of cast steel, a valve within the body having a stem portion extending exteriorly thereof; a relay mechanism connected to the valve stem for operating the valve and including a casing structure of cast iron, and means connecting the cast steel valve body and cast iron relay casing structure including steel rods each of which is welded at one end to the valve body and rigidly connected at the other end to the casing structure. 20

17. Apparatus according to claim 16 wherein the steel rods are tapped into the cast iron relay casing. 25

18. In operating mechanism for the motive fluid admission valve of a prime mover, the combination of an operating piston connected to the admission valve, pilot valve means for controlling the application of fluid pressure to the operating piston, means responsive to movement of the operating piston for restoring the pilot valve 30 means to neutral position in order to terminate movement of the operating piston, an operating member for moving said pilot valve means and having an extent of movement such that said admission valve may be completely closed at any 35 speed of the prime mover, and means for increasing the ratio of movement of said operating member to movement of said operating piston as said operating member approaches the position in which it effects complete closing of the admission valve. 40 45
